ARTICLE FEED MECHANISM

Alvin H. Bauman, Detroit, Mich., assignor, by mesne assignments, to United States of America as represented by the Secretary of the Navy

Application May 27, 1953, Serial No. 357,803

6 Claims. (Cl. 198—26)

This invention relates to feeding mechanisms for articles and has special use in connection with the process claimed in copending application, Serial No. 324,160, by Robert L. Henry.

This copending application describes a method of mass producing electronic equipment, and the instant mechanism may be used for feeding articles, as the ceramic wafers described therein, to a dryer, one by one. In so far as the present mechanism is concerned, the type of dryer supplied by this mechanism is not material, nor is it important that the articles be fed to a dryer at all. However, a part of the dryer disclosed in copending application Serial No. 344,694 and now Patent No. 2,742,711 by Harry M. Adams is shown herein, since the present use of the invention is with that dryer.

In the referred applications, it is explained that a ceramic wafer is the preference of article being handled, and each wafer has notches in the edges thereof, provided with a metalized, liquid coating. When the articles are received by the disclosed mechanism the coatings are still wet (prior to admission to the dryer) and thus require special handling to prevent smearing of the wet coatings. Accordingly, it is an object of the present invention to provide an article feeding mechanism that accepts the articles, assures that a proper number is fed to a rotating spider, the arms of which having elements that push the articles one by one into another device or to a stock pile. More specifically, an object of the invention is to provide an inclined guideway constraining the article travel, and in the guideway supply two reciprocating dogs spaced from each other a proper amount to define an article pocket that retains only a single article, so that when the dogs are reciprocated alternately, only one article is allowed to drop completely through the guideway for acceptance by the arms of the spider.

Another object of the invention is to provide means for timing the actuation of the dogs with the rotation of the spider so that the articles enter a track in which the spider arms are operable only at such time that they will fall between the spider arms.

A further object of the invention is to provide means in the travel of the spider arms for separating the arms from the track in which the articles are moved at or near the discharge end of the track to permit the articles to escape from the track without interference from the spider arms.

Other objects and features of importance such as various adjustments of the mechanism will become apparent in following the description of the illustrated form of the invention.

In the drawings:

Fig. 1 is a plan view of the feeding mechanism, and a part of a dryer track is shown adjacent to the mechanism to accept the articles that are fed thereto.

Fig. 2 is a side view of the feed mechanism of Fig. 1.

Fig. 3 is a sectional view in enlarged scale showing the article guideway of the mechanism and taken on the line 3—3 of Fig. 1 and in the direction of the arrows.

2

In the accompanying drawings one embodiment of the article feed mechanism is shown in detail. It consists of a base 10 adapted to be secured by bolts 12 or the like to a suitable support, adjacent to the device into which the articles are to be fed. In this instance the articles are fed into a heat dryer D that has a track 14 from the upper surface of which rise ribs 16 and 18 that serve as a support for the articles. The track is stationary while the articles on the track 14 are moved along the track by rods 10 66 (see copending application Serial No. 344,694 by Harry M. Adams).

Base 10 has an upper surface in which a substantially circular raceway 20 is formed, a part of the raceway containing a curved track 22 provided with a pair of spaced ribs 24 and 26 that form continuations of the ribs 16 and 18. In addition to the walls defining the raceway, there is a vertical and curved wall 28 along the outer edge of the curved track 22 to obviate the possibility of articles that enter the track 22 from skipping out of it. A spider 30 is secured to a vertical shaft 32 for rotation therewith, shaft 32 being rotated through a conventional gear connection with power shaft 34 that is timed by proper gearing to operate in coordination with the rods 66. The arms 36 of the spider are spring material, for example certain plastics or metals, and are sufficiently long that the outer ends thereof are slightly spaced inwardly of the periphery of the raceway 20 (Fig. 1). Although the spider arms may be used without help, each arm 36 has a roller 38 mounted on an axis normal to the arm length, and the rollers 38 contact a part of one edge of the article to be moved along track 22.

Means 40 operative when the spider arms 36 are near the end of track 22, that is slightly beyond it are provided on the upper surface of base 10, for lifting the spider arms 36 together with the pusher element or roller 38 of each, above the article that is being moved. With the feed mechanism used as suggested in Fig. 1, the purpose of having the spider arms elevated is to leave the articles deposited on track 14, permitting rods 66 to move them further. In the alternative, the feed mechanism could be used with devices other than dryer D, or could be used simply for depositing a number of articles in a container at a definite, known rate. Means 40 are shown as a cam 42 having a flange 44 in which there are slots 46 accommodating screws or bolts that hold the cam 42 fastened to base 10 in a selected position so that the arms 36 may ride thereover in their travel. The adjustment possibility of the cam is present so that the place of arms 36 on track 22 or beyond track 22 at which they are lifted over the articles conveyed may be regulated.

The inner wall 48 of the raceway 20 is curved toward the periphery of the base 10 at the place of article discharge to guide the articles smoothly as they are moved out of the feed mechanism. To minimize the amount which the spider arms 36 must be flexed for discharging the articles, an opening 50 is provided in wall 48 and constitutes a passage for rollers 38.

Means responsive to rotation of shaft 32, and hence actuation of spider 30, are provided to admit articles to the track 22. Preferably, these means comprise a support plate 52 held at an angle to the upper surface of base 10 and containing a chute with a guideway 54 (Fig. 3) opening at its lower end into track 22 and having an inlet track 56 at its upper end secured to plate 52. The guideway consists of strap 58 secured to plate 52 and supporting angle member 60. One surface of member 60 has ribs 62 and 70 fixed thereto and they are aligned with the ribs of track 56 as well as the ribs 24 and 26 of track 22. An apertured cover 72 is connected to plate 52 and member 60, closing the top of guideway 54, the cover 72 containing ribs 74 and 76 parallel to the ribs 62 and 70 and

preventing articles from escaping upwardly from the guideway or from stacking thereon.

The articles entering the guideway 54 are fed to track 22 in timed relation with the operation of the spider 38. The timing is accomplished by the use of a cam 78 having a plurality of camming surfaces equal in number to the spider arms adjustably secured to shaft 32, and a cam follower assembly associated therewith. It includes a follower 80 at one end of a push rod 82 constrained by a housing 84 adjustably secured to plate 52, and in which there is a pin 86 operable in a slot 88 in push rod 82. The opposite end of push rod 82 is bifurcated, accommodating one end of link 90 by a slot-pin connection, the opposite end of link 90 being slotted to receive a pin 92 on a rocker 94. The link 90 is pivoted intermediate its ends on pin 96 that is mounted on a dovetail, or an equivalent, supported block 98, the latter being adjustable to regulate the stroke of link 90 and hence, rocker 94. For block 98 adjustment, a screw 100, captive by its collar 102 in a bracket 104, is threaded in the block 98, whereby the block 98 may be moved in response to screw rotation. Set screw 105 is used to lock the block 98 in any selected position.

Rocker 94 is pivoted on a suitable pivot 106 and contains opposed slots 108 and 110 in which pins 112 and 114 are slidable. These pins are fixed to dogs 116 and 118, the ends of which are beveled to facilitate the movement of articles thereby. Suitable passages are provided in plate 52 to accommodate the dogs 116 and 118, and these passages open into passageway 54 to permit the dogs to work in and out of the passageway, extending transverse to the path of article travel, in response to actuation of the rocker 94. To maintain the above described linkage tight and maintain follower 80 on cam 78, a spring 120 is connected to link 90 and to a screw 122, the latter being adjustably mounted in a threaded block 124 which is, in turn, adjustably secured to plate 52 by screws 126 which are threaded to the plate 52 after passing through slots in the block 124.

Operation

The articles, as notched ceramic wafers, are gravity fed into the guideway 54, entering the upper end thereof by way of track 56. They slide on the ribs 62 and 70 until they encounter the stop formed by dogs 116 and 118. Assuming the position of the stop is as shown in Fig. 1 when the first wafer slides down the guideway 54, it will strike dog 118 and stop, other wafers behind it also being stopped. As the shaft 32 rotates, the link 90 is actuated, causing rocker 94 to withdraw dog 118 and insert dog 116 into the guideway 54, allowing the first wafer to drop down to the dog 116 and be held thereby. As the shaft 32 with its cam 78 is rotated further, the dog 116 is withdrawn from guideway 54 permitting the first wafer to escape, but all of the other wafers are held by the dog 118 which is extended at least partially across the guideway by the action of the rocker 94 which withdrew the dog 116.

As this initial wafer leaves the captive position, it slides on ribs 62 and 70 until it comes to rest on ribs 24 and 26 of track 22 for only an instant. To require the wafer to take the proper course in the transposition from guideway 54 to track 22, the wall 28 is used, together with its companion wall 128 on the opposite edge of track 22. Moreover, resilient fingers 130 and 132 fastened to cover 72 at the discharge end of guideway 54 are disposed over the track 22 for a short distance to prevent the wafer from bouncing or otherwise escaping from the path of the spider arm destined to move it along track 22.

Since the metering of wafers through guideway 54 is responsive to rotation of shaft 32 and the spider 30 is secured to the same shaft, the spider arms must operate in proper, timed relation with the wafer metering part of the devices. As the discussed imaginary first wafer comes to rest beneath resilient fingers 130 and 132, a spider arm approaches the rear edge of the wafer and the pusher ele-

ment 38 thereof then comes into contact with the outer part of one of the wafer notches. The element 38 is of a diameter sufficiently large to prevent any part of it from contacting the wet coating in the deeper part of the notch.

The wafer is moved along track 22 by the pusher element 38 until it leaves track 22 and, in the illustrated instance, enters track 14. Then the spider arm is elevated by riding over the cam 42 thereby leaving the wafer and following the raceway for subsequently moving another wafer that will be waiting beneath the resilient fingers 130 and 132.

It is understood that deviations from the specific forms of the invention disclosed herein may be made so long as they fall within the scope of the following claims.

15. What is claimed is:

1. In an article feed mechanism, a horizontal base, a chute carried by said base and inclined with respect to the upper surface thereof, said base having a curved track for the articles and said chute having an article guideway parallel therewith and in confronting relation with the curved track so that articles passing through said guideway enter said track, a vertical shaft in said base, a horizontal spider secured to said shaft for rotation thereby, said spider including spider arms that have article pusher elements carried near the outer ends thereof, said elements being disposed in said curved track, an article stop arranged to block said guideway, means responsive to rotation of said shaft and thus the position of said spider arms for momentarily removing said stop from said guideway to permit an article to pass through the guideway and enter said curved track, said stop removing means including a horizontal cam having a plurality of camming surfaces secured to said shaft, a cam follower in contact therewith, a link, a push rod connected to said link and said cam follower, and a rocker pivoted to said link and said stop.

2. The combination of claim 1 and an adjustment block on which said link is mounted, and means for adjusting the position of said block to thereby adjust the amount of motion imparted to said rocker by said link.

3. The combination of claim 1 and resilient fingers extending from said guideway beyond the ends of said guideway, to retain the articles in a predetermined travel when they leave said guideway.

4. In an article feed mechanism, a horizontal base, a chute carried by said base and inclined upwardly with respect to the upper surface thereof, a circularly curved track on said base, an article guideway in line with and connecting said chute and said curved track so that articles passing down said chute slide through said guideway onto one end of said track, a vertical drive shaft in said base, a spider including a plurality of resilient radially extending arms secured to said shaft for rotation therewith, said spider arms having pusher elements carried near the outer ends thereof and being disposed in said curved track, a horizontal cam member superimposed over said spider and secured to rotate with said shaft, said cam member having a plurality of camming surfaces equal in number to said spider arms, an article stop arranged to block said guideway, a cam follower in contact with said camming surfaces, linkage means connecting said cam follower to said article stop, whereby the article stop is adapted to be moved into and out of said guideway to allow an article to pass therethrough in response to movement of the cam follower.

5. The combination of claim 4, and means on said base adjacent the end of said track remote from said one end thereof to elevate said arms.

6. The combination of claim 5 and resilient fingers extending from said guideway into said track, to restrain the articles until said articles are engaged by the pusher elements of said spider arms.
